UNITED STATES PATENT OFFICE

GEORGE S. LEWIS, OF SPRINGFIELD, MASSACHUSETTS, ASSIGNOR TO J. STEVENS COMPANY, OF CHICOPEE FALLS, MASSACHUSETTS, A CORPORATION OF MASS SETTS.

PISTOL.

1,338,381.

Specification of Letters Patent. Patented Apr. 27,

Application filed May 17, 1919. Serial No. 297,856.

To all whom it may concern:

Be it known that I, GEORGE S. LEWIS, a citizen of the United States, residing at Springfield, in the State of Massachusetts, have invented certain new and useful Improvements in Pistols, of which the following is a specification, reference being had to the accompanying drawings, forming a part hereof.

10 This invention has for its object to produce a single-shot pistol, particularly adapted for target shooting, of simple, inexpensive and rigid construction, the details of improvement being pointed out more particularly hereinafter, with reference to the accompanying drawings in which the invention is illustrated and in which—

Figure 1 is a top view of the pistol closed.

20 Fig. 2 is a view of the same in vertical, longitudinal, central section.

Fig. 3 is a detail view of the barrel lock.

Fig. 4 is a view similar to Fig. 2, but showing the pistol broken.

25 Fig. 5 is a detail view in section on the plane indicated by the broken line 5—5 of Fig. 2, looking in the direction of the arrows.

30 Fig. 6 is a detail view in section on the plane indicated by the broken line 6—6 of Fig. 4, looking in the direction of the arrows.

The pistol comprises two main parts, the frame a , chambered at a' , as shown clearly in Figs. 2 and 4, with its grip pieces a^2 secured by bolts a^3 , and the barrel b secured in its sleeve or carrier b' which is pivoted in the frame at b^2 . In the left-hand side of the frame, as shown in Figs. 1 and 3, in 35 a recess a^4 is pivoted on a screw c' , a triangular barrel-latch c , provided with a milled surface c^2 and normally thrown forward by a spring which is shown in part at c^4 , so that its nose c^5 may engage a recess b^3 formed in the side of the barrel or 40 its carrier b' . To release the barrel, the latch is pulled back and when the barrel is again swung to a closed position it first presses the latch rearwardly and is then 45 engaged by the latch in its closed position, the lower edge of the latch being curved on a slightly eccentric arc so that it shall engage the barrel with a cam-like action and so prevent possibility of movement of the 50

barrel with respect to the frame while the pistol is closed.

In the under-side of the carrier b' is formed a dove-tailed groove b^4 , clearly in Figs. 4, 5 and 6, which receives the extractor d formed at its rear end at d' , to enter the recess b^6 in the carrier and the end of the barrel b to engage properly the cartridge, as clearly in Fig. 2. A dog d^2 is pivoted in a slot a^5 in the forward end of the frame a , having a flat heel d^3 to limit the movement of the dog when the pistol is opened by contact with the rear wall a^6 of the slot, and having a nose d^4 which, when the barrel is closed, enters the slot a^5 . The dog is normally pressed forward by a spring-pressed plunger d^5 which is pivoted in the frame, the forward movement of the plunger being limited by a pin d^6 . When the pistol is closed the extractor d and the dog d^2 occupy the positions shown in Fig. 2, but when the pistol is broken the nose d^4 of the dog, during the first part of the breaking movement, engages the end of the extractor d and moves relatively to the barrel, as shown in Fig. 4. During the last part of the breaking movement of the barrel the dog d^2 remains in its rest by reason of the contact of its heel d^3 with the rear wall a^6 of the slot a^5 , therefore its nose d^4 clears the forward end of the extractor d when the barrel reaches the position shown in Fig. 4 so that a cartridge is fully inserted in the carrier b' of the barrel and the extractor is moved forward its forward end acts against the inclined or cammed surface d^7 of the dog d^2 and thrusts the dog backward and ward out of the path of the extractor d . Finally, when the barrel reaches the position shown in Fig. 2, the forward end of the extractor d clears the nose of the dog d^4 and permits it to be snapped up by the spring plunger d^5 into the position shown in Fig. 2 in readiness to engage the barrel in the next breaking movement.

It will be noted further that the nose d^4 is formed with an inclined or cammed surface d^8 , best shown in Fig. 4, in the closing movement of the barrel b the incline d^8 strikes the frame at the point a^7 and thereby the extractor is thrown

ward and does not interfere with the closing movement of the barrel. The movement of the extractor in each direction is limited by a pin d^9 , the end of which travels in a slot b^6 in the under-side of the carrier b' .

The hammer e is pivoted in the frame, is acted upon by a main spring e' and plunger e^2 and is controlled by a combined trigger and sear e^3 , acted upon by a spring-pressed plunger e^4 , all substantially as usual. The hammer is completely inclosed within the chamber a' of the frame and is connected by a link e^5 with the finger-piece e^6 which is extended rearwardly through the frame so that the hammer can be cocked. The hammer acts as usual upon the firing pin f . The rear sight g , is shown in position in Figs. 1, 2 and 4.

It will be understood that changes in the form and relation of parts may be made to suit different conditions of use or the convenience of the manufacturer and that the invention is not limited to the precise construction shown and described herein except as pointed out in the claims.

I claim as my invention:

1. In a pistol, the combination of a frame, a barrel pivotally mounted on the frame, an extractor sliding on the barrel, and a dog pivotally mounted on the frame and having a flat heel to coöperate with the frame to limit the swinging movement of the dog and provided with means for co-operation with the extractor in the forward movement of the extractor whereby the dog

is moved out of the path of t to permit full forward movement the dog being free to engage t again when the closing movement of the barrel is completed.

2. In a pistol, the combination of a barrel pivotally mounted on the frame, an extractor sliding on the barrel, pivotally mounted on the frame, a nose to engage the extractor, inclined or cammed surface or above the nose to coöperate with the extractor in its forward movement, the dog is swung rearwardly out of the path of the extractor, the full forward movement thereof being free to engage the extractor during the closing movement of the barrel.

3. In a pistol, the combination of a barrel pivotally mounted on the frame, an extractor sliding on the barrel, pivotally mounted on the frame, a nose to engage the extractor, a pass out of engagement therethrough, breaking movement of the link, spring-pressed plunger carried and coöoperating with the dog to move the dog upward and return it to position, the extractor in the next forward movement of the barrel.

This specification signed this day of May, A. D. 1919.

GEORGE
